UNITED STATES PATENT OFFICE

HERMAN J. HAMMERLY, OF WALLINGFORD, CONNECTICUT, ASSIGNOR TO THE TRUMBULL ELECTRIC MANUFACTURING COMPANY, OF PLAINVILLE, CONNECTICUT, A CORPORATION OF CONNECTICUT

INCLOSED SWITCH

Application filed October 3, 1928. Serial No. 310,089.

This invention relates particularly to the class of inclosed switches which are operated by means of an external handle and in which each movable switch blade or contact is arranged to simultaneously make or break an electrical contact with each member of a pair of appurtenant stationary contacts to thus effect a double-make or a double-break in the circuit. It is a well known fact that a double-break switch of the preceding description will safely break a circuit of very much greater capacity than any form of single-break switch of a like size or any form of double-break switch in which the points of contact are not separated simultaneously.

One advantage of a double-break switch of this type is that, when the switch is in the off position, the movable contacts are dead and harmless and, being dead in that position, the box can be made quite a little shallower as it is not necessary to allow clearance space between the movable contacts and the adjacent parts of the inclosing box. In fact, it would not matter electrically if the movable contact actually touches the metal of the box when it is in the off position.

One object of my invention is to provide a very simple, rugged and practical form of double-break switch in which the cost of manufacture is comparatively low.

Another object is to provide a double-break switch construction in which the movable contacts are mounted on a movable insulating cross-bar or barrier which is interposed between the respective pairs of stationary contacts to form a guiding means for the movable contacts and which moves with the movable contacts in such a manner as to greatly assist in disrupting any arc formed in opening the switch.

Another object is to provide a double-break switch construction of a form which may readily be adapted for use in connection with a slate or marble base or a base of other machined insulating material.

Another object is to provide an inclosed double-break switch construction in which the base of the switch is spaced sufficiently away from the bottom of the box to provide

protected working room for the switch crank and the cross-bar connectors.

Another object is to provide a double-break switch construction having cross-bar connectors extending through the switch base and having metal guide plates for the connectors of such a form that they may readily be secured to a frangible base of slate or equivalent insulating material.

Fig. 1 is a front view of a switch embodying my invention the cover being shown open and the switch being of what is commonly termed a "meter testing" type although the invention is not limited to this particular type.

Fig. 2 is a transverse sectional view showing the switch box closed but with the switch in the open circuit position.

Fig. 3 is a side view and section showing the switch contacts and method of insulation and operation.

Fig. 4 is a perspective view of the parts of the switch which more particularly involve my present invention.

The box 10 and its cover 11 may be of any suitable type of construction.

The switch proper has a base 12 of insulating material which is supported above the bottom of the box by means of a number of brackets 13 so that there is plenty of working space beneath the base. The base is secured to the brackets by a number of screws 14.

The stationary contacts 15 and 16 are preferably in the form of spring jaws spaced apart from each other a short distance. The form illustrated employs three pairs of these contact jaws but the number of pairs is unimportant to my present invention. These contact jaws are secured to the base in any suitable manner.

The movable contact or switch blades 17 are mounted on the outer face of insulating cross-bar 18. These blades may be suitably secured as for instance by means of T-shaped anchorage members 19 riveted or otherwise secured to the blades and the anchorage members being secured to the insulating bar by means of an integral tang or rivet portion 20 which extends through an opening 21 in the

bar and is riveted over a washer 22 beneath the bar.

These anchorage members may have teeth or shoulders 19' adapted to be pressed into the insulating bar 18 when the tang is riveted in place. This obviates the necessity of slotting the cross-bar.

The cross-bar 18 is supported by crank connector rods 23 which preferably have integral tangs which are riveted to the cross-bar. These connectors are guided in slots in plates 24 which are secured to the base by screws 25. Plates 24 may be mounted on either the front or the back of the base or in pairs 15 in which case, the two plates would be on opposite surfaces and secured together by means of screws or rivets. The base is provided with cylindrical perforations 24' over which the plates 24 are mounted. These holes 20 24' are cut or drilled large enough to allow for the free passage of the connector rods 23.

The switch operating member in the form shown consists of the crank shaft 26 which is preferably pivoted in the opposite sides of 25 the box and has a handle 27 which extends outside of the box. The crank shaft passes beneath the base 14 and engages in slots 28 in the connectors 23.

To close the circuit, the handle 27 is usually moved so that the crank 26 pulls the connectors 23 toward the bottom of the box, and thus draws the switch blade 17 into the contact jaws 15 and 16. When the circuit is to be opened the handle 27 is moved in the opposite direction and the crank 26 thrusts the connectors 23 and the cross-bar 18 with its contact blade 17 outwardly thus breaking the circuit through the blade 17 and the jaws 15 and 16. At the moment of breaking the circuit the insulating cross-bar 18 is interposed 40 between the tips of the jaws 15 and 16 so as to intercept and disrupt any arc which may tend to form in the opening movement.

By reason of the insulating cross-bar being guided between the adjacent edges of the stationary contacts and the connectors being closely guided by the slots in the plates, it will be readily apparent that the movement of the operating crank or handle will cause 50 the movement of the blades in a direction substantially at right angles to the surface of the base and, at all times, the blades will be maintained in a relative position substantially parallel with the surface of the base and 55 with the outer ends of the stationary contacts, thus compelling a simultaneous engagement or disengagement of the movable blade with its respective pair of stationary contacts.

It is of course necessary that the circuit be 60 opened or closed simultaneously at each respective pair of stationary contacts, therefore the movement of the movable blade must be closely routed and the use of the accurately punched guide plates makes such a movement possible at a minimum expense. Ob-

viously it would be a very expensive operation to work rectangular or other shaped holes through a slate or marble base to closely fit the connector which passes through the base but, by the use of these guide plates, 70 it is only necessary to drill a round hole through the base large enough for the connector to pass through and then secure the comparatively very cheap guide plates in position.

75 I claim:

1. A switch including an insulating base, a pair of stationary contact jaws mounted on said base, an insulating cross bar movable between and guided by said jaws, a contact 80 blade mounted on said bar and adapted to electrically connect said jaws, a guide plate secured to said base and an actuating connector extending through said guide plate and connected at one end to said insulating bar.

2. A switch including an insulating base, a pair of stationary contact jaws mounted on said base, an insulating cross bar movable between and guided by said jaws, a contact 90 blade carried by the outer edge of said bar and adapted to electrically connect said jaws, an operating crank and an actuating connector extending through said base and operably connected to one end of said crank 95 and secured to said insulating bar at the other end.

3. A switch including an insulating base, a number of pairs of stationary contact jaws mounted on the base and spaced apart from 100 each other, an insulating cross bar movable between the jaws of each respective pair of jaws, contact blades carried by the outer edge of said bar and adapted to electrically connect each respective pair of jaws, an actuating connector extending through said base and secured to said insulating bar between 105 said blades, and an operating crank operably connected with said connector.

4. In an electric switch, an insulating carrier bar, a T-shaped anchorage member having its shank extending through said bar and secured thereto, and a switch blade extending at right angles to said bar and secured to the head of said anchorage member. 110

5. In an electric switch, an insulating base of slate-like material having three holes therein, a metallic guide plate mounted on said base and having oppositely disposed screw seats and an intermediate guide slot, screws passing through two of the holes in said base and secured to the screw seats in said plate, a blade carrying bar and connector secured thereto and guided in said guide slot and extending through the third hole in said base. 120

6. A switch including a slate base having a cylindrical perforation therein, a metal plate secured to said base and covering said perforation and having a slot in line with 125

said perforation, a movable switch member having a connector rod slidable in said plate and an operating member connected to said rod.

7. In an electric switch, an insulating carrier bar, a T-shaped anchorage member having a shank extending through said bar and having a head with edges abutting one surface of said bar, said edges having tooth-like shoulders indented into the edges of said bar, said shank being secured in said bar and a switch blade secured to the head of said anchorage member and extending in a plane transverse to said bar.

15 HERMAN J. HAMMERLY.
